UNITED STATES PATENT OFFICE.

WILHELM MADEL, OF NIEUKERK, GERMANY.

ALARM-CLOCK.

SPECIFICATION forming part of Letters Patent No. 460,751, dated October 6, 1891.

Application filed January 16, 1891. Serial No. 378,058. (No model.) Patented in Germany February 8, 1890, No. 52,769.

To all whom it may concern:

Be it known that I, WILHELM MADEL, a subject of the Emperor of Germany, residing at Nieukerk, in the Empire of Germany, have 5 invented a new and useful Minute-Alarm for Clocks, (for which I have obtained a patent in Germany, Serial No. 52,769, bearing date February 8, 1890,) of which the following is a specification.

10 The object of this invention is an alarm for clocks which allows of being adjusted to a certain minute. The new device is illustrated in the annexed drawings, in which—

Figure 1 is a vertical section of the clock. 15 Figs. 2 and 3 are detail views; and Fig. 4 is the front view of the work.

The device is essentially disposed as follows: A weight-gearing A is used in the known manner to impart oscillating movement to the 20 clapper *a* of the alarm-gong. The clapper-shaft *b* is provided with two pins *c d*, which bear by the pull of the alarm-weight against two corresponding arms *e f*, one of which *e* is revolvably and displaceably coupled with the 25 minute ratch-disk *e²*, while the other *f* is in the same relation to the hour ratch-disk *f²*. Said two arms *e f* are inclosed by a fork *k*, which prevents them from participating in the revolution of the two disks *e² f²*. The innermost tube *g* of the hand device carries at 30 the outer end the minute-hand *g'*, and at the inner extremity the minute-wheel *g²*. It is, moreover, surrounded by a tube, the outer end of which is provided with the adjusting-hand *e³* for the minutes, while it carries at 35 the inner side the minute ratch-disk *e³*. The latter has a cavity or rest which corresponds to a nose on the contiguous surface of the minute-wheel *g²*. By means of the spring *e'*, 40 Fig. 2, the minute ratch-wheel *e³* is pressed against the minute-wheel *g²*, whereby said

ratch-wheel *e³* falls with its rest over the nose of the minute-wheel *g²*, as soon as the latter occupies the corresponding position determined by the minute alarm-hand *e³*. 45 Thereby the arm *e*, connected with the minute ratch-disk *e²* recedes from respective pin *c*, which therefore occurs once an hour. A third tube shifted on carries the hour-hand *h* and the hour-wheel *h'*, and is surrounded with 50 another tube provided with the adjusting-hand *i* for the hours, and a disk *g³*, which is pressed by a suitably-placed spring *f'* against the hour-wheel *h'*, and sinks with a rest or cavity over a corresponding nose provided at 55 the front surface of the hour-wheel *h'*, as soon as the latter has assumed a certain position determined by the direction of the hour alarm-hand *i*. The arm *f* connected to the hour ratch-disk *f²* then undergoes displacement 60 and frees the corresponding pin *d*, which takes place once in twelve hours. If, subsequently, also the arm *e* connected to the minute ratch-disk *e²* is displaced in the aforescribed manner when the determined minute 65 has arrived, also the other pin *c* is released and the clapper-shaft *b* is allowed to swing by the pull of the weight.

What I claim, and desire to secure by Letters Patent of the United States, is— 70

In an alarm-work for clocks, the combination of the arms *e f*, bearing against the corresponding pins *c d* of the clapper-shaft *b*, with the minute ratch-wheel *e³*, the minute-wheel *g²*, the hour ratch-disk *f²*, and the hour-wheel *h'*, as described, and for the purpose 75 specified.

WILHELM MADEL.
